UNITED STATES PATENT OFFICE

2,433,921

TRANSMISSION HOIST

Nels O. Nelson, San Juan, Tex.

Application April 15, 1946, Serial No. 662,381

1 Claim. (Cl. 254—139.1)

1

My invention relates to improvements in transmission hoists for removing transmissions from automobiles and the like.

The invention is designed with the primary object in view of providing a simple form of hoist for lifting such transmissions through the floor of automobiles and removing the same out of the front door, and which is especially adapted for easy operation by one man, is safe, inexpensive to manufacture, and will not readily get out of order.

To the accomplishment of the above, and subordinate objects presently appearing, a preferred embodiment of my invention has been illustrated in the accompanying drawing, set forth in detail in the succeeding description, and defined in the claims appended hereto.

In said drawing:

Figure 1 is a view in side elevation of my improved hoist, in the preferred embodiment thereof, with parts broken away and shown in section,

Figure 2 is a view in plan, partly in section,

Figure 3 is a view in vertical transverse section taken on the line 3—3 of Figure 1 and drawn to an enlarged scale,

Figure 4 is a view in horizontal section taken on a line 4—4 of Figure 1 and also drawn to an enlarged scale.

Reference being had to the drawing by numerals, my improved hoist, in the illustrated embodiment thereof, comprises a V-shaped base 1 including a pair of side bars 2 converging to an apex web 3 provided with an upstanding socket sleeve 4. Caster wheels 5 beneath the ends of the side bars 2, and beneath the apex web 3 support said base 1.

A cylindrical post 6 arises from the socket sleeve 4 with the lower end thereof seated in and rotatable in said sleeve.

A cross head 7 is provided on the post 6 for vertical sliding adjustment thereon and having the form of an offset T-fitting comprising a vertical sleeve 8 slidably fitted on said post, and a horizontal cross sleeve 9 offset laterally to one side of the sleeve 8 and provided with a rear end counterbore 10 for a purpose presently clear.

A U-clamp 11 is fitted on the post 6 beneath the sleeve 8 for vertical sliding adjustment on said post to support the cross head 7 in different vertically adjusted positions.

A hand crank 12 extended through the clamp 11 and threaded into one side thereof, as at 13, provides for tightening the U-clamp 11, at will.

A tubular crane arm 14 extends horizontally from the cross head 7 with a rear end portion

2

suitably fitted and fixed in the front end of the sleeve 9. The bore 15 of the crane arm 14 is of the same diameter as the counterbore 10 of said sleeve 9.

5 A reel operating shaft 16 is rotatably extended through the crane arm 14 and the sleeve 9 with a working fit in the bore 15 and the counterbore 10 and with its front end extending out of the front end of the crane arm 14 and its rear end extending out of the rear end of said sleeve 9.

A small diameter flanged reel 17 is suitably fixed on the front of the reel operating shaft 16 and retained on said shaft by a nut 18, said reel having suitably fixed thereto for winding thereon a cable 19 provided with a terminal hook 20.

20 A ratchet wheel 21 and a hand crank 22 are suitably fixed on the rear end of the reel operating shaft 16 and secured thereon by a nut 23, the ratchet wheel 21 being confined against lateral displacement on said shaft 16 between the rear end of the sleeve 9 and said hand crank 22.

A ratchet dog 24 is pivoted, as at 25 on the sleeve 8 to override the ratchet wheel 21, the pivot 25 having the form of a bolt adapted to be turned 25 against the post 6 to lock the cross head 7 to said post against rotation independently of the post.

25 In using the described invention, the cross head 7 is first adjusted vertically on the post 6 to a height such that the crane arm 14 may be extended through the front door of an automobile, not shown, from which a transmission is to be removed. In so adjusting the cross head 7, the pivot 25 is first suitably loosened so that said cross head may be lifted on the post 6 to the desired position, after which the clamp 11 may be adjusted on said post 6, in a manner which will be clear, to hold the cross head 7 in adjusted position. The base 1 is then wheeled beneath the body of the automobile to extend the crane arm 14 through the front door until the reel 17 is in appropriate position for lifting the transmission. With the crane arm 14 thus extended, said arm may be swung laterally to align the reel 17 vertically with the transmission, the post 6 rotating in the socket sleeve 4 during such swinging of said arm, it being understood that after adjustment of the cross head 7, the pivot 25 is to be tightened to lock said cross head to the post 6. The ratchet dog 24 may then be lifted to disengage the ratchet wheel 21 so that the cable 19 may be lowered to engage the hook 20 with a suitable part of the transmission to be lifted.

With the ratchet dog 24 dropped into engagement with the ratchet wheel 21, the hand crank 22 may then be operated to cause, in a

manner which will be clear, the reel 17 to wind up the cable 19 and lift the transmission upwardly through the floor of the automobile and into a position such that by backing the hoist away from the automobile, said transmission may be removed out of said door. Obviously, the ratchet dog 24 and ratchet wheel 21 will hold the reel 17 against reverse rotation to maintain the cable 19 wound during this removing operation. The transmission may be replaced by substantially reversing the operations described in the foregoing, as will be understood.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claim.

What I claim is:

In a hoist of the class described, a wheel supported elongated base, a post at one end of said base having a lower end rotatably mounted on the same, a cross head vertically slideable on said post into different set positions, a clamp on said post vertically adjustable thereon to support said

cross head in the different set positions thereof, a crane arm extending horizontally from said cross head, to overlie said base and having a rear end fixed in the cross head, a shaft rotatable in said cross head and crane arm with a front end extending out of said arm and a rear end extending out of said cross head, a cable winding reel fast on the front end of said shaft, an operating crank for said shaft fast on said rear end thereof, and dogging means for said shaft, including a pivoted dog the pivot of which is adjustable to lock the cross head to the post.

NELS O. NELSON.
